MANIFOLDING DEVICE

Edward K. Bottle, Elmira, N. Y., assignor, by
mesne assignments, to American Sales Book
Company, Inc., a corporation of Delaware

Application September 12, 1929, Serial No. 392,045
Renewed May 4, 1932

4 Claims. (Cl. 282—22)

This invention relates to manifolding pads and sets of manifolding leaves, and has for its object the provision of a simple and practical construction of manifolding pad wherewith assurance of 5 manifold copying is bettered, and wherewith manifold copying and distribution of record leaves after separation from the pad is facilitated and promoted.

The invention accordingly comprises an article 10 of manufacture possessing the features, properties, and the relation of elements which will be exemplified in the article hereinafter described and the scope of the application of which will be indicated in the claims.

15 For a fuller understanding of the nature and objects of the invention reference should be had to the following detailed description taken in connection with the accompanying drawing, in which:

20 Figure 1 is a perspective view of a manifolding pad embodying the invention;

Fig. 2 is a perspective view illustrating one of the sets of record leaves of Fig. 1.

Referring now more specifically to the drawing, the pad illustrated in Fig. 1 is composed of 25 a plurality of relatively superposed sets of record leaves, each set including an intervening carbon sheet. One such set is illustrated in Fig. 2, wherein the numeral 1 indicates an original record leaf, 2 a duplicate record leaf, and 3 the intervening carbon sheet. In practice only the bottom face 30 of the carbon sheet 3 is coated with a transfer material, as for instance illustrated at 4, although it is to be understood that a double-faced carbon sheet may be utilized if desired.

35 Considering the arrangement of one set, as illustrated in Fig. 2, it will be apparent that inscription made upon the top face of the original record leaf 1 will be copied on the duplicate record leaf 2 by reason of the intervening carbon sheet 3. Each of the record leaves 1 and 2 is provided with a printed form, as for instance a bill form, indicated at 5 and 6.

For the purpose of retaining printed forms 5 40 and 6 in superposed registry with each other, and for making a convenient and practical pad, the several sets of leaves and sheets 1, 2 and 3 are superposed relatively to each other and bound together by staples 7. It is to be understood, however, that other practical means of binding the sets together in pad form may be utilized.

In the present embodiment, the leaves 1 and 2 in each set are folds of an integral record sheet folded along a longitudinal line or side line 8, the 45 outer ends of the folds being connected to each

other to form a pocket enclosing the carbon sheet 3. Referring to Fig. 2, it will be seen that the outer ends of these folds form the longitudinal edges of the record leaves, opposite to the longitudinal fold line. These longitudinal edges of the record leaves of each set are adhesively connected to each other, as by a line of paste indicated at 9, each of the leaves 1 and 2 having longitudinal weakening lines 10 between the pasted portion and the adjacent edge 11 of said carbon sheet. 5 Along the weakening lines 10 the pasted portion may be readily torn or parted from the main body of the record sheet. Adjacent one transverse end of the folded sheet is a transverse weakening line 12 along which the folded sheet may be parted 10 from the stub of the pad.

In this embodiment, it will be noted that in each set, the carbon leaf is bound in the stub by the staples 7. The carbon sheet may be provided with weakening lines in registry with the transverse 20 weakening lines 12 so as accurately to be parted along with the record leaves. The carbon sheet 3 not only lies between the record leaves 1 and 2 but also across the transverse weakening lines 12 in the latter leaves.

In use, inscription made upon the topmost record leaf 1 will be copied upon the duplicate leaf 2 and in the same relative position in the printed forms on the two leaves. During such inscription the carbon is positively held accurately in manifolding position between the leaves by the staples 7. After such inscription, the record leaves 1 and 2 may be grasped between the thumb and finger and separated from the stub by tearing along the weakened lines 12 and the registering, weakening line in the carbon sheet. It will be noted, however, that, after this tearing, the original and duplicate leaves will still be held by the paste 9 so that their printed forms will be held in registry, and the carbon will be held in the 30 pocket therebetween so as to be restrained from free movement. In this wise the carbon is retained between the original and duplicate leaves, although these latter are separated from the stub of the pad, so that inscription made on the separated original leaf will be assured of being copied on the underlying duplicate leaf. Inscription having been completed, the original and duplicate 35 may be parted by tearing off the pasted area along the weakened lines 10 and along a longitudinal 40 weakened line coincident with the fold 8.

It will be perceived that the printed forms on the record leaves 1 and 2 are very securely held in registry by reason of being bound to the stub as well as by the pasted connection 9 therebe-

tween, which latter is at a side of the pad adjacent the stub side, the edge 11 of the carbon sheet being outside the pasted area so as not to be affected thereby.

5 Furthermore, it is to be noted that the binding elements 1 lie in a general line which is disposed transversely of the manifolding pad or book and at substantially right angles to the line of the longitudinal fold 8 between the 10 original and duplicate record leaves, and at a similar angle to the opposite longitudinal edges of the record and transfer leaves. By means of this disposition of the binders, they will function to hold the top or original leaf 1 down in close 15 contact with the transfer leaf 3 even after severance of the paste connection 9. Because of this relative arrangement of the binders 1 and of the fold 8, the original leaf 1 is retained at all times in flat folded condition closely against the transfer leaf 3 and the duplicate 2. It is thus impossible for the original leaf 1 to swing outwardly away from the other leaves or otherwise to get out of position, and the transfer leaf is thus protected and effectively held in place at all 20 times by the closely contacting overlying original leaf 1.

The numeral 13 indicates a stop plate, the purpose of which is to underlie the undermost record leaf of a set so as to prevent copying on the lower set by the inscription being made upon the upper set. The stop plate 13 may consist of a relatively heavy manilla or cardboard leaf of proper consistency to prevent copying therethrough. As illustrated, the plate 13 is embodied in a flexible sheet of relatively heavy manilla paper which is of sufficient length to extend around the front end of the pad, as at 14, and underlie the pad to provide a backing portion 15, which may be secured to the bottom of 40 the pad through the intervention of the staples 7. After one set has been inscribed, the stop plate 13 may be inserted between the next two underlying sets prior to inscription upon the upper set of the latter.

45 Since certain changes may be made in the above article and different embodiments of the invention could be made without departing from the scope thereof, it is intended that all matter contained in the above description or shown in 50 the accompanying drawing shall be interpreted as illustrative and not in a limiting sense.

Having described my invention what I claim as new, and desire to secure by Letters Patent, is:

1. A manifolding pad including, in combination, a stub, relatively superposed sets of relatively superposed manifolding record leaves, each 5 set including two superposed record leaves with an intervening carbon sheet, said two leaves, in each set, including a longitudinally folded sheet the ends of the folds of which are connected to each other to form a pocket enclosing said carbon sheet, each set including its carbon sheet, forming a part of the pad stub. 10

2. A manifolding pad including, in combination, a stub, relatively superposed sets of relatively superposed manifolding, record leaves, each 15 set including two superposed record leaves with an intervening carbon sheet, said two leaves, in each set, including a longitudinally folded sheet the ends of the folds of which are connected to each other to form a pocket enclosing said carbon sheet, each set, including its carbon sheet, being bound in the stub of the pad, and the ends of the folds of the folded record sheet of each set having longitudinal weakening lines alongside their line of connection and outside the lateral 20 edge of the carbon sheet. 25

3. A manifolding pad including, in combination, a stub, relatively superposed sets of relatively superposed manifolding, record leaves, each 30 set including two superposed record leaves with an intervening carbon sheet, said leaves and sheets extending into and forming a part of the pad stub, said record leaves having weakening lines for detachment from the stub, said two leaves, in each set, including a longitudinally 35 folded sheet the ends of the folds of which are pasted together and have longitudinal weakening lines between the pasted portion and the adjacent edge of the carbon sheet.

4. A manifolding set comprising, in combination, a record sheet folded to provide two superposed leaves, the ends of the folds connected together and having longitudinal weakened lines for detaching the connected portions from the main body of the record sheet, and having transverse weakening lines adjacent one end of the folded sheet, and a carbon sheet lying between the folds of said folded sheet and across said 40 transverse weakening lines. 45

tween, which latter is at a side of the pad adjacent the stub side, the edge 11 of the carbon sheet being outside the pasted area so as not to be affected thereby.

5 Furthermore, it is to be noted that the binding elements 1 lie in a general line which is disposed transversely of the manifolding pad or book and at substantially right angles to the line of the longitudinal fold 8 between the 10 original and duplicate record leaves, and at a similar angle to the opposite longitudinal edges of the record and transfer leaves. By means of this disposition of the binders, they will function to hold the top or original leaf 1 down in close 15 contact with the transfer leaf 3 even after severance of the paste connection 9. Because of this relative arrangement of the binders 1 and of the fold 8, the original leaf 1 is retained at all times in flat folded condition closely against the transfer leaf 3 and the duplicate 2. It is thus impossible for the original leaf 1 to swing outwardly away from the other leaves or otherwise to get out of position, and the transfer leaf is thus protected and effectively held in place at all 20 times by the closely contacting overlying original leaf 1.

The numeral 13 indicates a stop plate, the purpose of which is to underlie the undermost record leaf of a set so as to prevent copying on the 25 lower set by the inscription being made upon the upper set. The stop plate 13 may consist of a relatively heavy manilla or cardboard leaf of proper consistency to prevent copying there-through. As illustrated, the plate 13 is embodied in a flexible sheet of relatively heavy manilla paper which is of sufficient length to extend around the front end of the pad, as at 14, and underlie the pad to provide a backing portion 15, which may be secured to the bottom of 30 the pad through the intervention of the staples 7. After one set has been inscribed, the stop plate 13 may be inserted between the next two underlying sets prior to inscription upon the upper set of the latter.

45 Since certain changes may be made in the above article and different embodiments of the invention could be made without departing from the scope thereof, it is intended that all matter contained in the above description or shown in 50 the accompanying drawing shall be interpreted as illustrative and not in a limiting sense.

Having described my invention what I claim as new, and desire to secure by Letters Patent, is:

1. A manifolding pad including, in combination, a stub, relatively superposed sets of relatively superposed manifolding record leaves, each 5 set including two superposed record leaves with an intervening carbon sheet, said two leaves, in each set, including a longitudinally folded sheet the ends of the folds of which are connected to each other to form a pocket enclosing said carbon sheet, each set including its carbon sheet, forming a part of the pad stub. 10

2. A manifolding pad including, in combination, a stub, relatively superposed sets of relatively superposed manifolding, record leaves, each 15 set including two superposed record leaves with an intervening carbon sheet, said two leaves, in each set, including a longitudinally folded sheet the ends of the folds of which are connected to each other to form a pocket enclosing said carbon sheet, each set, including its carbon sheet, being bound in the stub of the pad, and the ends of the folds of the folded record sheet of each set having longitudinal weakening lines alongside their line of connection and outside the lateral 20 edge of the carbon sheet. 25

3. A manifolding pad including, in combination, a stub, relatively superposed sets of relatively superposed manifolding, record leaves, each 30 set including two superposed record leaves with an intervening carbon sheet, said leaves and sheets extending into and forming a part of the pad stub, said record leaves having weakening lines for detachment from the stub, said two leaves, in each set, including a longitudinally 35 folded sheet the ends of the folds of which are pasted together and have longitudinal weakening lines between the pasted portion and the adjacent edge of the carbon sheet.

4. A manifolding set comprising, in combination, a record sheet folded to provide two superposed leaves, the ends of the folds connected together and having longitudinal weakened lines for detaching the connected portions from the main body of the record sheet, and having transverse weakening lines adjacent one end of the folded sheet, and a carbon sheet lying between the folds of said folded sheet and across said 40 transverse weakening lines. 45
